FLOORING CONSTRUCTION

George E. Swenson, Hastings on Hudson, N. Y.,
assignor to The Celotex Corporation, Chicago,
Ill., a corporation of Delaware

Application July 7, 1938, Serial No. 217,877

6 Claims. (Cl. 20—7)

In the laying of floor surfacing materials, that is in particular, floor surfacing materials which are of appreciable thickness and which are in the form of regularly shaped units laid side by side, difficulties are often encountered either in the laying of the material in connection with the finished surface due to expansion, contraction and the like. In addition, because of difficulties which sometimes arise due to expansion and contraction of floor surfacing materials, satisfactory finishing of the joints between adjacent units is often difficult since in general the joints between adjacent units should be sealed to prevent the entrance into the joints of moisture, dirt and the like.

In addition to the above mentioned deficiencies of flooring materials of the general character mentioned the step involved in laying such floors wherein the joints between adjacent units are filled or caulked with a mastic material is a slow and tedious procedure and furthermore, a complete filling of cracks between adjacent units with the mastic is difficult. Still further, when mastic joint fillers are used between adjacent flooring units it often happens that as the individual units expand and contract that the joints either open up due to the fact that the mastic is not securely adhered to each edge of adjacent units or that, due to expansion of the units, the mastic is forced up or mushroomed out of the joints.

It is a particular object of this invention to provide a construction of floor surfacing material wherein the various disadvantages and unsatisfactory performance of heretofore used floor construction and methods of laying flooring materials are overcome. Particularly it is an object of this invention to provide a flooring construction and method of laying floors wherein for floor surfacing materials laid in the form of a plurality of individual units provision is made at the joints between adjacent units to allow for expansion and contraction of the units, to provide a satisfactory and permanent joint seal and to provide a joint between adjacent units which is permanently filled with a material which will neither shrink, so that cracks between adjacent units are left open, nor will it mushroom out of the joints. Still additional advantages of my construction and additional objects of my invention will become apparent on reading the following specification when considered in connection with the accompanying drawing.

In the accompanying drawing:

Figure 1 is a perspective view of a fragmentary portion of my improved floor construction;

Figure 2 is a fragmentary plan view of my floor construction illustrating a corner where four units come together; and

Figure 3 is a cross sectional view taken on line 5 3—3 of Figure 2.

In the drawings in the various figures thereof, similar reference numerals are used to designate similar elements in the several views.

In the drawing there is illustrated a surface indicated by numeral 10 to which surface is to be applied a floor surfacing material 11, applied in accordance with my improved method of application and incorporating my improved construction. It is of course to be understood that the base floor 10 to which the finished floor surface is to be applied shall be fairly smooth and even, or if this is not the case, that such surface has been leveled up by the application thereto of suitable substance such as a setting mastic or by 15 suitably grouting with cement or the like.

The units illustrated in the drawing as comprising the finished flooring may be suitable floor units such as cork tile, wood tile or the like but such are preferable units which are formed from 20 fibre insulating board as a base material which base material is saturated with suitable asphaltic or compounds of generally like physical properties, as, for example: asphalt of between 110 and 180 degrees F. melting point, or other saturant 25 having physical characteristics more or less similar thereto, as for example, by saturation with an equivalent pitch.

The units 11 may conveniently be $\frac{1}{2}$ inch thick and 12 inches by 12 inches in dimensions 30 and more or may not be provided with a bevel around the top edge, which bevel in the drawing is indicated at 12.

According to my construction, the finished floor units 11 are laid on the base floor 10 and adhered 35 thereto by a suitable adhesive or mastic indicated at 13, which adhesive or mastic should have the characteristic that it does not set up hard, that is such mastic should have the characteristic of permanent limited plasticity so that as the units 40 11 tend to expand or contract due to atmospheric changes or the like or due to other causes, the units 11 may adjust themselves and possibly shift their positions slightly to compensate for any slight movement which may be brought about 45 due to the causes mentioned.

According to my invention, there are provided for placing in the joints between adjacent units 11 relatively thin strips of joint filler material 14 which strips of joint filler material are conveniently prepared of width equal to the height 50

or thickness of units 11, or if the units are beveled to a width or height equal to the dimension from the back of unit 11 to the base of its surface bevel 12. The joint filler strips may be furnished as strips of any convenient length or may be prepared in rolls which can be cut to length as may be required. Preferably the joint filler strips 14 if provided in individual strip form will have the ends of the strips scarfed as indicated at 15 or if the filler strip 14 is furnished in rolls, lengths when cut therefrom may be scarfed either as they are cut from the roll or afterwards as may be convenient.

In laying the finished floor units 11 they may be laid with four corners of adjacent units coming together as indicated in Figure 2 or they may be laid in any other convenient arrangement as for example, considering Figure 2, the units indicated to the right of the vertical joint may be displaced laterally so that the horizontal joint is broken and is not continuous across the finished floor. It is, of course, to be understood that the pattern in which the units 11 are laid will depend somewhat on the shape of the units which may be square or rectangular or the like or even triangular or other regular shape and is also dependent upon the floor pattern which it is desired shall be obtained.

The application of my invention is independent of the shape of the units 11 and of the pattern in which such units are laid and is generally applicable.

The joint filler strip 14 comprises a base of fibrous material which may conveniently be a felt such as is ordinarily used in the manufacture of saturated roofing products which felts are available in different thicknesses but which conveniently for the purpose hereof will preferably be approximately of $\frac{1}{8}$ inch thickness. The felt comprising the base for the joint filler strip 14 is preferably saturated with a relatively soft and ductile asphalt as for example, a Venezuelan residual asphalt of about 105 to 120 degree F. melting point or with an equivalent coal-tar pitch or the like.

The felt base of the joint filler strip 14 should be saturated with the saturant to the extent of approximately 200% of its weight and subsequently for the purpose hereof the such saturated sheet should be preferably surface coated on both sides or faces with a relatively thin coating of asphalt or other substance depending upon the saturant used which surface coating will preferably be of the same substance or substances used for saturating but of a slightly higher melting point as for example, the felt, if saturated with asphalt of 105 degree F. melting point will preferably be coated with asphalt having a melting point of say 110 or 120 degree F. It is to be understood that the procedure of saturation and coating the felt as described is substantially the same as the steps involved in the preparation of saturated and coated roll roofing and that the desired joint filler strips 14 may be conveniently prepared from substantially any good grade of saturated and coated roll roofing.

In the laying of a finished floor of the floor surfacing units 11 in accordance with the inventions hereof, the base 10 being reasonably level and smooth as has been before referred to, has applied thereto over an area somewhat in excess of the area of a single unit of the finished flooring 11 a continuous layer of the mastic or adhesive 13 which layer of mastic, in general practice, will be of thickness of say about $\frac{1}{8}$ inch more 75

or less, dependent to a large degree upon the specific characteristics of the mastic being used.

After mastic has been applied to the base 10 as described, a unit 11 is laid thereon, preferably 5 laid on the mastic a slight distance from the final position to be taken by the unit and then the unit is under firm pressure pushed or moved a slight amount diagonally to properly position the unit.

10 The next step in laying a finished floor surface of units 11 according to my invention, is to take a strip of the joint filler material prepared as hereinbefore described, which strip of material will have applied to its face a suitable solvent, 15 which if the strip is saturated and coated with asphalt may be any usual solvent for asphalt as for example, gasoline, naphtha, carbon-disulfide or other appropriate solvent. In applying the solvent to the surface of the joint filler material 20 it is to be understood that the aim of such application is that of rendering the surface of the joint strip sticky or tacky and that the solvent should consequently be applied only in limited quantities to achieve such purpose and that appreciable excess of the solvent other than that required to merely moisten the surface should not be applied.

The solvent when applied to the surface of the joint filler material will render the surface tacky 30 or sticky and thus the next step in applying the finished floor will be to lay one of the joint filler strips 14 with its surface rendered tacky as described against an edge of a previously applied finished floor unit 11. Due to the fact that the 35 surface of the strip 14 has been rendered tacky as described, the strip will, when pressed into contact with the edge of a unit 11 adhere and as the solvent evaporates the asphalt or equivalent material with which the strip 14 is coated will harden or go back to its original consistency 40 but the strip 14 will be securely adhered to the edge of the unit 11. If the unit 11 in its manufacture has had its edges coated with an asphalt, it will of course result that the solvent applied to the face of the fibre joint filler strip 14 will 45 somewhat soften the asphalt on the edge of unit 11 against which the strip 14 is applied, in which case the asphalt coatings, one on the edge of unit 11 and one on the face of strip 14 will fuse together and strip 14 will be securely held in place.

The next step in the laying of the finished floor surface is to apply further mastic 13 followed by the application of a further unit 11 which unit will of course be bedded in the mastic and firmly pushed into place against the exposed face of the strip 14 which had previously been applied as described. In accordance with the foregoing description, the contacting faces of the applied joint filler strips 14 and floor units 11 will be firmly adhered.

By repeating the various steps of the application of the finished floor as described it will of course result that the such flooring may be applied over the entire area which is to be floored and it will result that the finished floor surface is to all intents and purposes a continuous and unbroken surface over the entire area to which the finished floor has been applied.

In the finished floor, the joint filler strips 14 serve to securely adhere the edges of adjacent floor units 11, through the intermediary of the strip 14 and the adhesive carried thereby and to provide an exposed surface without cracks through which water may seep in, between or be-

hind the units and without cracks which may fill up with dirt or the like. Nevertheless there is provided a finished floor which may expand and contract or move slightly or weave without opening up joints between units 11 since the strip 14 is flexible and is somewhat expandable and contractable across its width or thickness, when considered in the position which it has in the finished floor surface.

In applying the joint filler strips 14, it is advisable that the strips be applied so that they lap over joints between adjacent units such as is shown in Figure 2, in that joint which is vertical when viewing the drawing from the bottom of the sheet, so that the joint in the strip will come at a point such as that indicated by numeral 15. It is of course readily understood where a filler strip 14 extends across a joint as has just been described, that a filler strip in the direction of right angles thereto cannot extend across the joint between adjacent units but that in such case it will merely abut the previously applied filler strip.

In accordance with the above described construction and following the methods of application as set out in detail, it is readily seen that in the finished floor each of the units 11 is securely bound into the whole and that without open cracks or joints provision has been made for expansion and contraction such as may occur due to atmospheric changes in temperature and humidity or from other causes.

While the joint filler strip has been specifically described as prepared in accordance with the general procedure of the manufacture of roll roofing, it is to be understood that the filler strip may be made from other materials, as for example, it may be prepared by suitably saturating and coating a thin sheet made in accordance with the general procedure of the manufacture of fibre insulating board, or it may be prepared from any other suitable material which will provide a finished product having the desired characteristics therefor. The finished floor units 11 may be saturated fibre insulating board as was particularly described or they may be of practically any other flooring material which is prepared in units for laying and for example, such finished flooring units may be cork, tile or wood units or the like, it of course being understood that my methods hereof and inventions are not very satisfactorily applicable unless the finished floor units have appreciable thickness say of about $\frac{1}{8}$ inch as a minimum up to $\frac{1}{2}$ inch or substantially any greater thickness in which it is desired that the units may be made and applied and that in any case the joint filler strips 14 are cut in proper width or height to extend through the thickness of the finished floor when applied.

The various suggested alternatives of various features of my invention are of course to be comprehended as within the scope of the inventions hereof and it will be readily understood that other alternatives and variations therefrom will be

readily apparent to those skilled in the art, and it is intended that such shall be comprehended within the scope hereof.

The inventions hereof having been fully disclosed and described in detail, I claim:

- 5 1. In a floor construction comprising a floor receiving base and a protective wearing surface applied thereto, the combination with the applied wearing surface comprising a plurality of units 10 laid on said base in spaced side by side relation and adhered to the floor receiving base by a layer of plastic adhesive, of strips of impregnated and coated fibrous material adhered to the edges of adjacent units and filling the spaces therebetween, whereby a joint filler is formed between the contiguous units allowing the applied wearing surface to expand and contract.
- 15 2. In a floor construction comprising a floor receiving base and a protective wearing surface 20 applied thereto, the combination with the applied wearing surface comprising a plurality of units laid on said base in spaced side by side relation and adhered to the floor receiving base by a layer of plastic adhesive, of strips of fibrous material adhered to the edges of adjacent units 25 and filling the spaces therebetween, and the said strips filling the spaces between adjacent units comprising sheet form felted fibrous base material impregnated with an asphaltic substance, whereby the strips between contiguous units completely 30 seal the joints formed thereby and allow expansion and contraction of the units.
- 35 3. A floor covering comprising an assemblage of spaced units, fibrous strip material in the spaces between the units, and the fibrous strip material asphalt saturated and coated adhered to the edges of the units and securing the units in a unitary floor covering assemblage, whereby the units are adapted to expand and contract.
- 40 4. The combination with a floor covering comprising an assemblage of spaced asphalt saturated fibre board units, of asphalt saturated and coated fibrous strip material in the spaces between the units, and the strip material adhered to the edges of the units and securing the units in a unitary floor covering assemblage, whereby a continuous and sealed exposed floor covering comprising expansion joints is formed.
- 45 5. The combination with a floor covering comprising an assemblage of spaced asphalt saturated fibre board units, of asphalt saturated strip material in the space between the units, the strip material having on its surfaces a coating of a substance adapted to become adhesive upon application of a solvent thereto and by said coating 50 adhered to the edges of the units to secure the units in a unitary floor covering assemblage.
- 55 6. As an article of manufacture, a joint filler strip for spaced tiling units comprising fibrous material asphalt saturated and coated, and the strip adapted to become adhesive upon the application of a solvent whereby the strip is adapted 60 to adhere to contiguous units forming a joint.

GEORGE E. SWENSON.
